UNITED STATES PATENT OFFICE.

WILLIAM ELY, OF PROVIDENCE, RHODE ISLAND.

ELECTRIC SWITCH.

SPECIFICATION forming part of Letters Patent No. 648,555, dated May 1, 1900.

Application filed February 19, 1897. Serial No. 624,185. (No model.)

To all whom it may concern:

Be it known that I, WILLIAM ELY, a citizen of the United States, and a resident of the city and county of Providence, in the State 5 of Rhode Island, have invented a new and useful Electric Switch, of which the following is a specification.

The purpose of my invention is to provide an electric switch adapted to make or break 10 with sudden rapid positive movement one or more circuits or to transfer the load with like movement from one or more circuits to other circuits located either in the same plane or at an angle of one hundred and eighty degrees or 15 less relatively to each other and to automatically lock itself releasably at the termination of each movement.

My invention consists in the novel construction, combination, and arrangement of 20 the knife actuating and locking mechanism.

In the accompanying drawings, Figure 1 is a perspective view of an electric switch constructed according to my invention. Fig. 2 is a side elevation showing the knife actuating 25 and locking mechanism. Fig. 3 is a partial section on line 3 3 of Fig. 2. Fig. 4 is a side elevation showing the application of my invention to a switch having a throw of only ninety degrees. Fig. 5 is a perspective view 30 illustrating another feature of my invention.

Similar reference-numerals indicate like parts where they occur in the drawings.

1 represents the base, constructed of insulating material, its surface being formed either 35 in a single plane or by two plane surfaces arranged angularly to each other. 2 and 3 are supports or housings rigidly secured upon said base. 4 is a shaft journaled in said housings and provided, if desired, with means, as 40 adjustable collars 5 and 6, for preventing endwise movement or play of said shaft. The knives or contact-arms 7 and 8 are preferably beveled on their upper and lower edges and are secured to an insulating-block 9, in turn 45 secured upon the said shaft and carried thereby. A crank or arm 10, rigidly secured upon said shaft, extends at right angles therefrom and is rotatable therewith. The free end of said crank-arm is fitted for engagement 50 releasably, at the termination of its movement in either direction, with a spring-controlled pivoted catch 15 16, whereby it is locked in

position. Said catches may be formed, as shown, with laterally-extending lugs 15' 16', adapted for engagement by a spring 17, by 55 which the pivotal movement of said catches is controlled. Pivotal movement of said catches, respectively, is induced by the contractual engagement with them for the purpose of releasing them from engagement with 60 the free end of the crank-arm 10 of an extension-arm 13 of a lever 11, loosely pivoted upon the shaft 4 and provided, if desired, with an insulated handle 12. Such extension-arm may be either in line with said lever, as shown 65 in Figs. 1 and 2, or laterally directed therefrom, as shown in Fig. 4. An extensible spring 14, secured to the free end of said crank-arm 10 and to the said lever 11 at a point intermediate of the length of the latter, 70 serves both as a means for connecting said lever and crank and as a means for actuating said crank after it is released from the catches 15 or 16.

18 and 19 are contact posts or brushes secured upon the base in the ordinary manner and connected with the main wires (not shown) of a circuit. 20 and 21 are other contact posts or brushes similarly secured upon the base in line with the first-mentioned 80 posts and connected with the service-wires. (Not shown.) The described posts are arranged, as shown, at one side of the shaft. On the other side of said shaft are other contact-posts 22 and 23, secured upon said base and 85 connected with the main wires (not shown) of another circuit, and 24 and 25 are still other contact-posts secured upon said base in line with the posts before mentioned and connected with the service-wires (not shown) of said 90 other circuit.

It will be noted that the lever 11 being pivoted loosely upon the shaft will have movement thereon without reference to the movement of said shaft and that its extension end (offset, if necessary, for the purpose) will at nearly the completion of the rotation of the lever contact with the under side of the crank-arm 10 and serve as a means for imparting initial positive movement to said 100 crank and its shaft to start the contact-knives from the contact-posts and overcome the frictional and other resistance which might tend to retard the movement of the knives.

Modifications in the parts shown may be made without departing from the principle of my invention. Other forms of spring may be employed to control the movement of the 5 catches. Springs as a means for controlling the movement of the catches may be dispensed with, in which case the catches may have capacity to yield and react spring-like for purposes of locking and releasing the 10 crank-arm 10. The catches may also be dispensed with, and in this form of my invention the extension end of the lever 11 will when brought into contact with said crank-arm act, as hereinbefore described, to impart 15 initial positive movement to the said crank-arm, shaft, and the parts carried by the latter to overcome the frictional and other resistance between the contact knives or plates and the contact posts or brushes. The 20 tensile spring 14 will, as hereinbefore described, act to accelerate and complete the rotative movement of said crank-arm and the parts connected to and moved by the latter.

I prefer to dispense with the insulating-block 9 and to construct the rotatable shaft 4 entirely of insulating material and to secure the contact knives or plates directly upon said shaft. I have shown in Fig. 5 a convenient form of embodying this feature of 30 my invention, in which the shaft 9 is constructed of insulating material and provided at either end with journals, preferably of metal. Such shaft is mounted upon the base for rotatable movement, as hereinbefore described. By this construction I am enabled 35 to obviate the liability of the current jumping from one contact member to the metallic shaft and thence to the other contact member, and thereby forming a short circuit.

40 I claim as my invention and desire to secure by Letters Patent—

1. The combination with the base-plate of insulating material, the shaft arranged parallel with said base-plate, and one or more 45 contact knives or blades carried on one side of said shaft, of the corresponding sets of circuit-terminals arranged at opposite sides of the shaft in the plane of the movement of the contact-blade, the actuating-lever loosely

held upon said shaft, and the spring connecting the shaft with the actuating-lever, whereby upon the movement of the actuating-lever in either direction the spring connection will cause the independent sudden transference of the contact-blade from one set of circuit- 55 terminals to the opposite set in a plane perpendicular to the plane of the base-plate.

2. The combination with the base, the shaft of insulating material arranged parallel with said base, and one or more contact knives or 60 blades carried on one side of said shaft, of the corresponding sets of circuit-terminals arranged at opposite sides of the shaft in the plane of the movement of the contact-blade, the actuating-lever loosely held upon said 65 shaft, and the spring connecting the shaft with the actuating-lever, whereby upon the movement of the actuating-lever in either direction the spring connection will cause the independent sudden transference of the contact-blade from one set of circuit-terminals to the opposite set in a plane perpendicular 70 to the plane of the base, substantially as specified.

3. In an electric switch, the combination 75 with a base, of a shaft of insulating material rotatably mounted on said base one or more contact knives or blades carried on one side of said shaft, a crank-arm secured upon said shaft, spring-controlled catches adapted to 80 engage and lock said crank-arm at the termination of its movement in either direction, a lever loosely pivoted upon said shaft and rotatable without reference to the movement of the latter, and adapted to move said respective 85 catches against the resistance of their controlling-spring, and a spring connecting said lever and crank-arm and adapted to rotate said crank-arm when the latter is otherwise released.

In testimony whereof I have hereunto set my hand, in presence of two witnesses, this 18th day of February, 1897.

WILLIAM ELY.
